STEAM BOILER

James W. Armour, Worcester, Mass., assignor to
 Riley Stoker Corporation, Worcester, Mass., a
 corporation of Massachusetts

Application September 18, 1933, Serial No. 689,937

5 Claims. (Cl. 122—235)

This invention relates to steam boilers, and more particularly to water-tube boilers having a transverse horizontal water drum which serves to connect a lower bank of tubes to an upper bank.

When boilers of this type are operated at high ratings, and particularly when water walls are provided which discharge into the drum, there is a tendency for steam to accumulate in the upper portion of the drum and prevent water from entering the tubes in the upper part of the upper tube bank. This condition is aggravated when side water walls are provided, since they cause a concentration of steam in the end portions of the drum. As a result, the tubes located in the upper part of the upper tube bank and near the side walls may receive insufficient water to protect them from overheating.

It is accordingly one object of the present invention to overcome these difficulties and to provide a construction which will decrease the concentration of steam in the upper portion of the drum and thus allow more water to enter the tubes of the upper bank.

It is a further object of the invention to provide means for distributing the steam more uniformly lengthwise of the drum when side water walls are connected to the ends of the drum.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a vertical longitudinal section through a steam boiler and furnace, the section being taken on the line 1—1 of Fig. 2;

Fig. 2 is a section on the line 2—2 of Fig. 1; and Fig. 3 is a detail view of a baffle plate.

In the drawing I have illustrated a steam boiler comprising a rear lower water drum 10, a front upper water drum 11, and a steam and water drum 12 located above the drum 10. These drums are arranged with their axes parallel and horizontal. The drum 10 is connected to the drum 11 by a bank of upwardly and forwardly sloping water tubes 14, and the drum 11 is connected to the drum 12 by a bank of upwardly and rearwardly sloping water tubes 15. The drums 10 and 12 are connected by a bank of substantially vertical water tubes 16. A steam drum 17 is mounted above the front water drum 11, and the drums 12 and 17 are connected by a row of steam tubes 18 which support refractory material 19 arranged to form a roof for the boiler. Walls 21 are arranged to provide a furnace chamber 22 beneath the lower tube bank 14, and baffles 23 direct hot gases from the furnace successively

across the tube banks 14, 15 and 16 to a gas outlet 24.

In order to protect the furnace walls and at the same time generate steam by the absorption of radiant heat and thus prevent excessive furnace temperatures, I preferably provide a row of vertical water wall tubes 26 at each side of the furnace. These tubes extend between lower headers 27 and upper headers 28. The lower headers 27 are supplied with water from the drum 10 by means of downcomer tubes 30 leading from the drum to the rear portions of the headers. The rear portions of the upper headers 28 are connected to the steam and water drum 12 by upcomer tubes 31, and the front portions of the headers 28 are connected to the front water drum 11 by upcomer tubes 32. At the front of the furnace I provide a row of vertical water wall tubes 34 which extend between the drum 11 and a horizontal header 35. This header is supplied with water from the drum 11 by means of a row of downcomer tubes 36 leading from the drum to the header and located outside of the tubes 34. The downcomer tubes 36 are protected from the heat by the refractory material of the furnace wall.

At the rear of the furnace I have shown a row of vertical water wall tubes 38 which extend between the drum 10 and a horizontal header 39. This header is supplied with water from the drum 10 by means of a row of downcomer tubes 40 leading from the drum to the header and located outside of the tubes 34. The downcomer tubes 40 are protected from the heat by the refractory material of the furnace wall.

With the construction as so far described, there will be a large amount of steam discharged into the drum 11, and this steam will tend to accumulate in the upper portion of the drum and prevent the entrance of water into the tubes in the upper part of the bank 15. Moreover, this steam concentration will be more pronounced near the ends of the drum, since the upcomer tubes 32 deliver a large amount of steam from the side water walls.

In order to overcome this difficulty, I provide means for baffling the steam which is released in the drum 11 and for directing the steam rearwardly so that a larger portion thereof will enter the tubes in the lower part of the bank 15. Moreover, I preferably deflect some of the steam from the end portions of the drum toward the center thereof. The preferred construction illustrated comprises a baffle plate or deflector 42 generally rectangular in shape and extending longitudinally within the lower portion of the drum. This baffle plate slopes upwardly and rearwardly, the lower front edge of the plate being located in front of the upper or discharge ends of the front water wall tubes 34. On the lower surface of the plate 60

42 I have shown a number of ribs or vanes 43 which are angularly positioned so that they are directed rearwardly and toward the center of the drum from each end thereof. These vanes deflect some of the steam toward the central portion of the drum and thus tend to equalize the steam distribution throughout the length of the drum, while the baffle plate 42 deflects the steam toward the rear of the drum and thereby causes 10 the steam to be distributed more evenly among the tubes of the bank 15.

In order to assist the baffle 42 in obtaining the desired steam distribution, I preferably provide a baffle plate 45 in the lower water drum 10. This 15 baffle 45 extends rearwardly and upwardly above the upper ends of the rear water wall tubes 38, and deflects the steam rearwardly which is discharged by these tubes. As a result, this steam enters the tubes in the upper portion of the front 20 drum 11, where it mingles with the steam which is rearwardly deflected by the baffle 42. The baffle plate 45 has a further advantage in that it prevents the entrance of steam into the lower ends 25 of the lower tubes in the bank 14. These tubes are subjected to intense radiant heat, and should have an ample supply of water free from steam.

The operation of the invention will now be apparent from the above disclosure. The furnace 22 is fired in any suitable manner, and the hot 30 gases flow across the tube banks 14, 15 and 16 to the gas outlet 24. Water circulates downwardly in the tube bank 16 and upwardly in the tube banks 14 and 15. Steam which is generated in the various tubes is finally released in 35 the drum 12 and flows through the tubes 18 to the drum 17, from which it is withdrawn for use. Water flows from the drum 10 downwardly through the tubes 30 to the header 27 and thence upwardly through the side water wall tubes 26, 40 the headers 28, and the upcomer tubes 31 and 32. Water flows from the drum 11 downwardly through the tubes 36 to the header 35 and thence upwardly through the front water wall tubes 34. The downcomer tubes 40 supply water from the 45 drum 10 to the header 39, and this water flows upwardly through the rear water wall tubes 38 and back to the drum. The steam and water mixture discharged by the tubes 38 is deflected rearwardly by the baffle plate 45 and enters the tubes 50 in the upper portion of the bank 14. This not only protects the lower tubes of the bank by ensuring an ample supply of water free from steam, but it also causes more of the steam to be released in the rear portion of the drum 11. The steam 55 which is delivered to the drum 11 by the tubes 32, 34 and 14 is deflected rearwardly by the baffle plate 42 and flows upwardly along the rear wall of the drum. As a result the steam is distributed more uniformly among the vertically spaced tube 60 rows in the bank 15. At the same time, the vanes 43 deflect steam from the end portions of the drum toward the center, and thus tend to overcome the steam concentration at the ends of the drum caused by the side water wall upcomers 65 32. The deflector plates 42 and 45 are inexpensive to manufacture and install, and they can be easily removed to permit access to the tubes for cleaning.

Having thus described my invention, what I 70 claim as new and desire to secure by Letters Patent is:

1. A steam boiler comprising a transverse horizontal water drum, a lower bank of tubes connected to the drum, an upper bank of tubes connected to the drum, walls forming a furnace chamber beneath the lower tube bank, water 5 wall tubes associated with the side walls of the furnace chamber and arranged to discharge steam and water into the end portions of the drum, and baffle means within the drum to deflect steam toward the central portion of the 10 drum.

2. A steam boiler comprising a transverse horizontal water drum, a lower bank of tubes connected to the drum and sloping rearwardly and downwardly therefrom, an upper bank of tubes 15 connected to the drum and sloping rearwardly and upwardly therefrom, walls forming a furnace chamber beneath the lower tube bank, water wall tubes associated with the side walls of the furnace chamber and arranged to discharge 20 steam and water into the end portions of the drum, and baffle means within the drum to deflect steam both toward the central portion of the drum and toward the rear wall thereof.

3. A steam boiler comprising a transverse horizontal water drum, tubes connected to the lower portion of the drum and arranged to discharge steam and water into the drum, water wall tubes arranged to discharge steam and water into the end portions of the drum, a bank of tubes connected to the upper rear portion of the drum, a baffle plate mounted within the drum and sloping upwardly and rearwardly to deflect steam toward the rear wall of the drum, and vanes on the lower surface of the baffle plate which are 35 angularly positioned and directed rearwardly and toward the center of the drum from each end thereof.

4. A steam boiler comprising a horizontal water drum, a lower bank of tubes connected to the drum and sloping downwardly and rearwardly therefrom, an upper bank of tubes connected to the drum and sloping upwardly and rearwardly therefrom, a row of water wall tubes connected to the drum in front of the lower bank, and an 45 upwardly and rearwardly sloping baffle plate mounted within the lower portion of the drum and above the water wall tubes, said plate extending part way toward the rear wall of the drum and serving to deflect steam from the 50 water wall tubes rearwardly.

5. A steam boiler comprising a horizontal rear water drum, a horizontal front water drum at a higher elevation than the rear drum, a bank of substantially vertical downcomer tubes connected 55 to the upper rear portion of the rear drum, a bank of inclined steam generating tubes extending from the front upper portion of the rear drum to the front drum, a row of water wall tubes connected to the rear drum beneath the bank 60 of steam generating tubes, and a baffle plate mounted within the rear drum and above the water wall tubes, said baffle plate sloping upwardly and rearwardly from the front wall of the drum and extending part way toward 65 the opposite wall of the drum to deflect steam discharged by the water wall tubes away from the ends of the lower steam generating tubes without preventing the flow of water from the downcomer tubes to the steam generating tubes. 70

JAMES W. ARMOUR.
